Frank E. Liverance, Jr.

UNITED STATES PATENT OFFICE.

FRANK E. LIVERANCE, JR., OF WYOMING PARK, MICHIGAN, ASSIGNOR TO THE
McCASKEY REGISTER COMPANY, (INCORPORATED IN 1914,) OF ALLIANCE,
OHIO, A CORPORATION OF OHIO.

LEAF FOR FILING APPLIANCES.

1,273,242.

Specification of Letters Patent. Patented July 23, 1918.

Application filed August 13, 1915. Serial No. 45,431.

To all whom it may concern:

Be it known that I, FRANK E. LIVERANCE, Jr., a citizen of the United States of America, residing at Wyoming Park, in the county of Kent and State of Michigan, have invented certain new and useful Improvements in Leaves for Filing Appliances; and I do hereby declare the following to be a full, clear, and exact description of the invention, such as will enable others skilled in the art to which it appertains to make and use the same.

This invention relates to filing leaf constructions. It is an object and purpose thereof to form a leaf of sheet metal at the same time constructing spacing sections integrally with the body of the leaf to permit the spacing of the leaves apart a distance when they are joined together in operative relation. Another object of the invention is to construct a leaf from sections, the sections being adapted to be connected together to form leaves of various sizes in accordance with the number of sections that are secured together which may be made a greater or less number as desired. Various other objects and purposes will appear as understanding is had of the embodiment shown in the accompanying drawings, in which—

Figure 1 shows in perspective a leaf formed of sheet metal on the front and back of which a single bill or the like may be filed.

Fig. 2 is a view showing the blank from which the leaf shown in Fig. 1 is formed; and

Fig. 3 is a perspective view of a leaf formed from a plurality of sections, one of the sections being removed from the remainder of the leaf to illustrate its construction.

Like reference characters refer to like parts throughout the several views of the drawings.

The blank from which the leaf illustrated in Fig. 1 is formed compromises a body 1^b having an upper extension 2^b, wings 3^b at each side and a lower extension 4^b. The extension 2^b is turned to form the upper strengthening and finishing rod 2 shown in Fig. 1, being bent along the dotted lines indicated in Fig. 2 to form said rib. Wings 3 are turned one in front of the body 1^b and

one to the rear along the dotted lines indicated to make the spacing sections while the extension 4 is bent upon the dotted lines shown in Fig. 2 to form a rectangular tube adapted to receive the bar 5, rectangular in cross section, which at each end is provided with a pintle 5^a, whereby it may be pivotally mounted in any suitable support.

Leaves thus formed may be mounted in any suitable support, one behind the other. The spacing sections 3 serve to keep the leaves separated and bills or the like may be retained on both sides of the body 1 by use of any suitable construction of bill retaining clip as will be readily understood. This leaf is very cheaply manufactured and at one side, both on the front and rear faces thereof the leaf is open for the reception or removal of bills.

In the construction of the leaf illustrated in Fig. 3 a plurality of sections are provided, each consisting of a body 6 provided at the top with a rib 2^a similar to the rib 2 of the construction shown in Fig. 1, while the outer sections of the leaf are formed at spaced apart intervals on their outer edges with spacing members 7 similar to members 3, part of which are turned forward and part to the rear as shown. On their inner edges each of the outer sections is formed with a plurality of tubular members 8 bent so as to project both ahead and back of the body of the sections. The intermediate sections of a leaf are provided on both edges with the tubular members 8 which are so located as to fit between the members 8 of the outer sections. When placed together the continuous opening through the various tubular members 8 may receive a vertical tie 9 to rigidly connect the sections together. Of course if desired the outer members 7 on the outer sections may be eliminated or formed in various other ways.

Each section at its rear edge is bent into a rectangular tube as shown at 4^a and when a plurality of sections are connected together a single rod 10, rectangular in cross section, may be inserted through the aligned tubes. Adjacent the lower edge of each section a portion of the body and of the tube 4^a is removed as shown at 11 within which a link 12 may be placed, it having spaced apart upper and lower members adapted to receive the bar 10 thus securing the link firmly to

the leaf. Each link at each end is formed with hinge portions 13 adapted to receive a pintle whereby the links may be hinged together to make a continuous chain of links, 5 whereby a plurality of the leaves may be joined together in hinged relation at their lower ends.

With this construction of leaf the width of it may be varied at will by merely introducing a greater or less number of intermediate sections between the outer sections, connecting them together by the ties 9 and using a single bar to secure them together at their lower ends. Various modifications 15 in detail may be resorted to without departing from the invention which is defined in the appended claims and all modifications in structure falling within the scope of said claims are to be considered as comprehended 20 by my invention.

I claim:

1. A filing leaf including a plurality of sections lying side by side extending the full length of the leaf, and means for securing the sections together in rigid relation to each other at adjacent edges thereof, substantially as described.
2. A filing leaf comprised of a plurality of sections located with the edges thereof adjacent each other, and means for tying the adjacent edges of the sections together to form a rigid leaf.
3. A filing leaf comprised of a plurality of sections, each section being provided with devices interengaging with like devices on an adjacent section, and means for securing the said devices of adjacent sections together.
4. A filing leaf comprised of a plurality of sections, means for connecting the edges of adjacent sections together, and separate

means for securing all of the sections together at one end thereof.

5. In a filing leaf, a body of sheet metal having a tubular member located at one end, and spacing members turned from the body at its edges, substantially as described.

6. In a filing leaf, a plurality of sections, tubular extensions formed at the edges thereof, said extensions on adjacent sections being interengaged, and a tie bar inserted through said extensions to tie the sections together.

7. In a filing leaf, a plurality of sections, tubular extensions formed at the edges thereof, said extensions on adjacent sections being interengaged and in alinement, a tie bar inserted through the alined extensions of adjacent sections, a tubular member formed at the end of each section, said members also being in alinement, and a tie bar inserted through all of said tubular members, substantially as described.

8. In a filing leaf, a plurality of sections, rectangular tubular sections formed at the edges of the sections and projecting in front and back thereof, said extensions on adjacent sections being interengaged and in alinement, a tie bar inserted through the alined extensions of the adjacent sections, a tubular member formed at the end of each section, said members also being in alinement, and a tie bar inserted through all of said tubular members, substantially as described.

In testimony whereof I affix my signature in presence of two witnesses.

FRANK E. LIVERANCE, Jr.
